UNITED STATES PATENT OFFICE.

WILLIAM ROWE, OF MARRICKVILLE, NEAR SYDNEY, NEW SOUTH WALES,
AUSTRALIA, ASSIGNOR TO ROWE'S PATENT LOCK AND BLOCK LIMITED,
OF SYDNEY, NEW SOUTH WALES, AUSTRALIA.

RAILWAY-TRAFFIC-CONTROL SYSTEM.

No. 812,597.

Specification of Letters Patent.

Patented Feb. 13, 1906.

Application filed February 23, 1905. Serial No. 246,875.

To all whom it may concern:

Be it known that I, WILLIAM ROWE, railway-signal fitter, of Mayville, Victoria Road, Marrickville, near Sydney, in the State of New South Wales and Commonwealth of Australia, have invented Improvements in Railway-Traffic-Control Systems, of which the following is a specification.

This invention relates principally to the control of railway traffic by means of telegraph block systems or those systems in which, the railway-line being divided into sections, the entry of a train or engine into a section is "blocked" by means of signals until a telegraphic message is received by the rear signal-man from the forward end of such block-section intimating that the previously-entered train or engine has advanced out of such block-section and that the line in such block-section is clear; but this invention is also applicable in part to other than telegraphic block systems of railway-traffic control.

In a telegraph block system of railway-traffic control the line or permanent way is divided into sections or blocks, hereinafter termed "block-sections," having in advance and at rear the attendants who work the signals and mutually control the departure and entry on the block-section between them of traveling vehicles, hereinafter referred to as a "train." These attendants or signal-men may work on station-platforms or in signal boxes or cabins, and each has a telegraph block instrument, (for each block-section under his control,) hereinafter called the "instrument." Each instrument has a sending or operating key or device, with, preferably, an indicator, and has a receiving-indicator, preferably in the form of a miniature semaphore. The sending lever, key, or device of the instrument, hereinafter termed the "operating device," has an automatic electromechanical lock in electrical connection with an insulated rail or other rail-contact at the advance end of the block-section, whereby the departure of a train out of said block-section will release said lock. The operating device of the block instrument carries bridges or other devices to make and break necessary electric circuits. Systems such as these are now known as "positive lock and block systems" and are exemplified by "Rowe's lock and block," described in great part in British

Letters Patent No. 19,505 of September 30, 1901, granted to me. In the working of such positive lock and block systems at certain times, as when traffic is slack, it is desirable to extend the length of the block-sections, and to do this intermediate instruments in intermediate signal boxes or cabins must be dispensed with or electrically "cut out" and the line-wires switched into through-circuits. Thus two or more block-sections are united into one continuous longer one with active advance and rear signalmen, and the intermediate cabins may be closed, with the block instruments therein excluded from the system. In such systems as those described in the before-mentioned Letters Patent on the switching through of the line-wires the outdoor semaphore-signal giving authority to pass the excluded signal-cabin could and would not operate, owing to the absence of an electrical current to energize the electromagnet of the said outdoor semaphore-signal, (said current controlled by the departure of the train from the now longer block-section being switched through to the active signal-cabin in rear.) Further, in such systems without the precautionary methods and devices of this present invention it is possible that a signalman retiring from an intermediate or excludable cabin, wherein the instruments are for a time to remain idle, may err in closing his apparatus and switching through the cabins in advance and in rear of him at the wrong moment, as when there is a train in his advance block-section and another in his rear block-section, and thus when these are united having the two trains in the one (longer) block-section to the danger of both said trains, and at the same time it is advantageous and practically a necessity that the outdoor semaphore-signal be freed and be capable of operation from any desired point, as a near platform or station, when the intermediate signal-cabin is excluded.

The main objects then of this present invention are to insure that the instrument in the intermediate cabin cannot be cut out and that the instrument-circuit between the rear and advance cabins of the to-be-united or longer block-section cannot be made continuous until the original rear section is clear of vehicles or obstructions and that the said united or longer section cannot

again be separated into the shorter sections under control of intermediate cabins until likewise the rear section is clear of vehicles or obstructions, to insure that the outdoor 5 semaphore-signal controlling the entrance to the original advance section at an intermediate or excludable signal-cabin may be operated by supplementary mechanical devices from any desired point, as from a near platform or station, and to insure that such supplementary devices are inoperative when said intermediate or excludable cabin is active or included in the system, and, further, to insure that the intermediate cabin cannot 10 be excluded while conflicting points are set in the block - sections or outdoor signals of such points signal the line as "foul" and that when said points are so set the attendant cannot give "line clear" to the cabin in rear, 15 and, further, to insure (this being not only applicable in intermediate or excludable cabins, but in all cabins) that when conflicting points are set "line clear" cannot be transmitted to either the advance or rear cabin 20 until the points are in normal safety position or no longer conflict, and, contrariwise, to insure that after "line clear" has been transmitted to the rear cabin conflicting points cannot be set to foul the path of the train accepted 25 until after the arrival of such train at the signal protecting such points. The nature and function of the methods and apparatus by which these objects are attained are as follows: (a,) the combination (in the excludable 30 cabin) with revolving switching through-contacts, as well understood, and the slide-bar of the instrument of a check-bar or retaining-bolt in such a manner that the electrical switching contacts cannot be operated to cut out 35 the instrument until the departure of a train from the operator's rear section and its entry into his advance section releases the electro-mechanical lock of said slide-bar, which in turn in its locked position holds the said 40 check-rod or retaining-bolt from movement, and so that on such release of the electro-mechanical lock the contacts may be operated to switch through the instrument circuit to cause said check-bar or retaining-bolt to retain or lock said slide-bar while the switching 45 contacts are in the cut-out position; (b,) the combination with said check-bar or retaining-bolt of a similar electro-mechanical lock to that on the slide-bar whose electromagnet is 50 energized on the closing of circuit by the train over an additional insulated rail or rail-contact at or about the point in the line where the outdoor signal controlling the entrance to the advance block-section, herein- 55 referred to as "starting-signal," is situated and on the closing of said circuit by the manipulation of a switch (in the cabin) for such purpose; (c,) the combination with the slide-bar of the instrument of a supplementary elec- 60 tromechanical lock of similar construction to

the main electro-mechanical lock on the slide-bar (preferably arranged on one leg of the slide-bar of the instrument bifurcated for the purpose) and having its electromagnet in a battery-circuit closed by a train on an additional 70 insulated rail or other rail-contact at a pre-determined position in the line, preferably near the signal protecting said points, generally the "home" signal, and a check-bar or retaining-bolt connected with a locking-pin 75 of the operative lever of joints of cross-overs, sidings, or offsets adapted to be thrust across the supplementary leg of the slide-bar as it releases or unlocks said points-lever and to be prevented from being so thrust across until after the energizing of the electromagnet of said supplementary electro-mechanical lock; (d,) the combination with the outdoor 80 semaphore-signal of the excludable cabin of a supplementary manually-operative lever 85 at any convenient position and similar locks on the switching through-contacts in said cabin and on the signal-lever and a key common to both said locks; but in order to illustrate the best method now known of carrying 90 this invention into practical operation and to assist in defining the novelties thereof reference will now be made to the drawings accompanying and forming part of this complete specification. 95

Figure 1, shown in three parts, each on a separate sheet, shows diagrammatically a double line of railway divided into block-sections with a complete installation of mechanism and electrical connections of three signal-cabins controlling said block-sections, the intermediate one of which is excludable, so that the two outer ones may be united to form one longer block - section controlled from the two outer signal - cabins. Fig. 2 100 is a diagrammatic view of the switching through-contacts in an intermediate or excludable cabin, showing the operating device of the block instrument therein with its electro-mechanical lock and a check - bar or retaining-bolt having also an electro-mechanical lock and showing also such parts of the instrument-circuit and the circuits of the two said electro-mechanical locks as are necessary to explain the working. Fig. 3 is a front elevation, 105 partly in section, of the operating device of a block instrument adapted to allow the exclusion of said instrument from the system and further adapted to lock the operative levers of points in the block-section and having 110 omitted for the sake of simplicity the cover and tumblers of the mechanical or key lock of the switching through-contacts; and Fig. 4 is a partial plan of the mechanism shown in Fig. 2. Fig. 5 is a partial elevation of an outdoor semaphore-signal adapted to be electro-mechanically operated from the signal-cabin of a block - section and to be manually mechanically operated from another position. 115

In the main the arrangement and combi- 120

nations of parts of this present improved Rowe's lock and block system follow closely those described and illustrated in the specification of the before-mentioned British Letters 5 Patent No. 19,505 of 1901, with such modifications and novel variations and constructions as now to be described.

The up-line 1 and the down-line 2, forming the permanent way, are divided, as shown, 10 into two block-sections, each of which has the necessary mechanical and electrical accessories as by reason of the before-mentioned patent are now well known, and these are diagrammatically shown as in the block-sections and in signal-cabins, (represented by the capital letters A, B, and C.) The intermediate or excludable cabin B has for each line revolving switching through-contacts well understood, (represented at 150 for the 15 up-line and at 151 for the down-line,) and also the ordinary bell signaling-circuit 160 has a switching-out device 161 for cutting out the bells therein and making said circuit 160 continuous from A to C.

25 The operating device or slide-bar 9 of the block instrument in addition to the lock actuated by electromagnet 10 has a check-bar or retaining-bolt 101, adapted to reciprocate under the armature-catch and in front of the 30 stop on said slide-bar 9, so that said slide-bar is locked by said check-bolt in danger position. This check-bar 101 is made integral with the sliding bolt 102 of a mechanical or key lock whose key works the tumblers (not 35 shown) of said lock and a rack 103, gearing in the pinion 104 on the spindle of the revolving switching through-contacts 105. These contacts, which are separately numbered 501, 502, 503, 504, 505, and 506, are carried by a 40 cylinder 500, mounted between the respective rows of contacts 1 to 9 in the several cut-outs 150 and 151. The contacts 501, 502, 503, and 504 are for connecting the contacts 1 to 9 of opposite rows, and the contacts 505 and 506 are 45 for connecting adjacent contacts of the same row when the cylinder is in different angular positions. This check-bolt 101 cannot be thrust across the bar 9 in front of the stop thereon until the armature catch is lifted by 50 the magnet 10, energized by the circuit joined up by a train passing over rail-contacts 8 as it leaves the block-section, even when said armature-catch so lifted leaves a clear passage for it. This check-bolt 101 cannot be thrust 55 across (by reason of the stop on the bar 9 being presented to it) while the electromagnet 13 holds said bar 9 in the line-clear position. Again, this check-bolt 101 being operated by the bolt 102, which also operates the revolving 60 contacts 105, insures that said contacts cannot be so operated while the armature-catch is in place denoting "train or line" (said catch presenting a barrier for the passage of said check-bar) or while the magnet 13 is energized in giving the signal "line 65

clear" to the rear cabin, (when the stop on the check-bar presents the barrier.)

The key of the mechanical lock of the switching through-contacts is arranged to operate the bolt 102, check-bar 101, and contacts 105 and also to operate the mechanical or key lock applied to lock the supplementary manually-operated lever, as well understood, of the outdoor semaphore-signal or starting-signal of the block-section and is in control of 70 the signalman when the intermediate cabin B is included in the system and in control of the stationmaster or other responsible person when said cabin is excluded. This key further cannot be withdrawn from said operating-lever unless said lever be locked in danger position nor from the lock of the switching through-contacts unless said contacts are in the cut-out or cabin-excluded position.

The check-bolt 101 may have on its rear end, as indicated in Fig. 2, an electromechanical lock consisting of a stop 111, a permanent magnet 112, an electromagnet 113, and an armature-catch 114. In a branch of the out-door signal-circuit is a circuit from a rail-contact 115 through a manually-operative switch 116 in the cabin, through the revolving through-contacts and said electromagnet 113, so that the armature-catch 114 will not release the check-bolt 101 unless the attendant has manipulated switch 116 and the train is upon the rail-contact 115. This check-bolt electromechanical lock in like manner may be utilized to guard the points of sidings and cross-covers.

The operating device of the block instrument in addition to the lock indicated by electromagnet 10 and its armature has a second lock with a like magnet 120, this acting on one limb 121 of the slide-bar 9, bifurcated 105 for the purpose. In addition to the mechanically-locked cut-out check-bolt 101 (whether or not it has an electromechanical lock) there are two additional check-bolts—an upper one, 124, adapted to thrust across in front of the 110 stop 123, and the other or lower one, 125, to abut with its end against the bolt 102 when the check-bolt 101 is in action, (or when the cabin is excluded). These check-bolts 124 and 125 are connected to a bell-crank 126, the 115 other member of which operates a locking-pin 127, adapted to enter a locking-orifice in the draw-bar 128 of the points-operating lever 129. The bell-crank 126 is on a spindle operated by handle 130. It will be seen that 120 the points-lever cannot be operated, being locked by a pin 127 in draw-bar 128, until the armature-catch is lifted by electromagnet 120 out of the way of check-bolt 125, and this armature-catch is only lifted when the circuit 125 through the electromagnet 120 is closed by reason of a train arriving at a rail-contact normally open at a predetermined point, such as 133, Fig. 1, and when the cut-out is in action said points-lever cannot be operated 130

by reason of the abutment of the check-bar 125 against the bolt 102, preventing the operation of handle 130 and the releasing of the holding-pin 127.

5 The outdoor semaphore-signal will be provided with a suitable arm and may also have an audible signal device. It also has weighted reverse-lever 34, anchoring-armature 39, and fixed electromagnet 38, as before described. In this case the weighted lever 34 is connected, by means of a rod 140, having a slot or elongated eye 141, to the loose one, 142, of a series of three weighted levers 142, 143, and 144, and which loose lever has a flange or lip 145 projecting over the other two levers 143 and 144. The lever 143 is connected by cord or chain 146 to the manually-operative lever in the signal-cabin and by cord or chain 32 over pulley 33 on lever 34 to the anchoring-armature 39, so that the cabin may operate said lever 143 and when the electromagnet 38 is energized to depress the lever 34 and so exhibit the "all right" signal, the elongated eye 141 allowing of said movement without interference with the other lever 144 and connections. When the electromagnet 38 is deenergized, the signal will fall to normal danger position, allowed by said eye 141 to do so without effect on the other mechanism. The other lever 144 is connected by cord or chain to the supplementary manually-operative lever at a platform or station or other desired point, so that when said lever 144 is in its elevated position the signal is 35 at "danger," and when the cord or chain is hauled upon it is depressed and allows lever 142, if free of lever 143, to descend by gravity and by means of connecting rod 140 to the lever 34 place the lever at "all right" without 40 interfering with the devices of the signal-cabin operative lever.

The specification of the previous patent hereinbefore referred to and the foregoing explanation of modifications and additions thereto, together with the drawings herewith, wherein the parts bear the distinguishing numbers referred to in the specification of said previous patent, will enable the working of this "Rowe's lock and block system" as 45 now improved to be practically carried out; but to facilitate the understanding of these present improvements a brief description of the operation of the system is now added.

Assuming the signalman at A has asked 55 signalman at B by means of the usual bell-signals for "line clear" for an up-train, B will respond by drawing forward the slide-bar 09 of his block instrument until the armature 012 is brought up to the poles of the retaining-magnet 013. The contact-bridge 018, having joined up plates 019 and 020, the retaining-magnet is energized and will hold the slide-bar in the line-clear position. The up-line circuit is from earth and battery 057 60 at B to retaining-magnet 013, thence to block-

instrument contact 020, bridge 018, and contact 019 on slide-bar of block instrument, thence by wire 059 to contact 061, bridge 060 and contact 063 of crossover points lever contacts, (these contacts are for breaking the line and joining alarm-circuit when the points levers are operated or siding-keys are out for shunting purposes,) thence along wire 064 to contacts 4 and 3 of up-line cut-out switch 150, along line 064, becoming line 64, to normally-closed rail-contact 7 in advance of the starting-signal at A, thence by wire 64 to lightning-arrester 152, relay 65, wire 66, indicator 67, wire 68, contact 69, armature 70 to earth. The indicator 67 at A shows "line 80 clear," and the relay 65 in lifting the selecting-armature 54 breaks the alarm-circuit at contacts 87 88 and joins up contacts 53 of the outdoor signal-circuit. This outdoor signal-circuit starts from battery 50 through switch 85 153, along wire 51, through normally open starting-signal-lever contact 29, (which contacts upon the signalman at A operating his outdoor starting-signal lever complete the outdoor signal-circuit, as described in British 90 patent hereinbefore mentioned to provide that the outdoor signal may be lowered,) bridge 27, and contacts 27 and 28, along wire 55, through armature 54, contact 53, line 52, reverser-magnet 38, detonator 46, line 51, 95 back to battery 50. Upon the up train entering the section A to B and operating the normally open alarm rail-contact 5 in advance of cabin A the alarm will not now be given, because the branch circuit is open at contacts 87 and 88; but on operating normally closed rail-contact 7, situated slightly in advance of rail-contact 5, the instrument-circuit 64 will be broken, causing the slide-bar 09 at B to fly to its normal danger position, where 100 it will be locked until the train passing over rail-contacts 8 out of the section releases the lock by operating the normally open releasing-lock contacts in rail-contact 7 at B. The up-line releasing-lock circuit at B is as follows: from earth and battery 004 through rail-contact 8 at B, line 005, through contacts 5 and 6 of up-line cut-out switch, through line 200, and releasing-lock 010 to earth. This completes the operation of the 115 train passing through the section A B. The operation of the system as the up-train passes through the section B to C is similar to that just described, the circuit being as follows: The up-line instrument-circuit at C 120 is through contacts operated by such levers in the interlocking machine as ought not to be moved after a train has been accepted. This causes the "line clear" to be automatically revoked should these levers be interfered with, as described in the before-mentioned British patent. Assuming that "line clear" has been given by C to B for an up-train, the instrument line-circuit is from earth and battery 057 at C, wire 058, retaining-magnet 125 130

013, to block-instrument contact 020, bridge 018, and contact 019 on slide-bar of block-instrument wire 059 to crossover-points-lever-contacts lever when normal, contacts 061 and 5 063 and bridge 060 of contacts operated by a points-lever and for the purpose of automatically revoking the "line clear" should the levers connected therewith be interfered with by similar contacts 261, bridge 260, and 10 contact 263, operated by the points-lever at C, thence by wire 064 to contacts 79 and 80 of rail-contacts normally closed at B, (taking the place of the relay 78, referred to in British patent before mentioned,) thence by wire 64 15 through contacts 1 and 2 of up-line cut-out 150 at B, lightning-arrester 154, relay 65, wire 66, indicator-coils 67, wire 68, contact 69, armature 70, wire 71 to earth 72.

The operation of the system on the down-20 line is the same as the up. The circuits are shown on the plan, all the signals being at "danger" for the down-road.

The signal-box at B is shown "included" in the system; but when "excluded" the circuit is switched on the cut-out instruments 25 150 and 151. For instance, the up-line wire 64 will pass from terminal 1 to terminal No. 3 of the up-line cut-out 150 by wire 064, 64 to rail-contact 7 at A, thence to relay 65, indicator 67, and to earth through 68, 69, and 70. The operation of including the intermediate signal-box, a description of the up-road being sufficient, is as follows: The signalman at B will wait until a train from A is passing over 30 his normally open alarm-rail contact 5 in advance of the starting-signal, when he will draw out the pull-bar 202, attached to the bridge 203 of the up-line cutting-in contact, causing the electromagnet 113 of the up-line 35 cut-out lock to be energized and release the check-bar 101. By means of the key obtained from the supplementary signal-lever attendant he can then thrust said check-bar clear of the slide-bar of the instrument and

40 at the same time operate the switching, through contacts 150, to cut in the up-line. This cutting-in circuit is as follows: commencing at the outdoor-signal battery 50, wire 51, terminals 7 and 9 of up-line cut-out, 45 through electromagnet 113, wire 92, bridge 203, which will be drawn by the signalman, onto contacts 204 and 205, wire 92 to rail-contact 5 and rail-contact 7, contacts 87 and 88, wires 89 and 56 and switch 154, and by 50 wire 86 back to battery 50. When the signalman at B desires to switch out, he must wait until the last train accepted by him has passed into his advanced section and released the lock on the slide-bar of his block instrument. He then turns the key of the switching 55 through-contacts 150 or 151 to cut out the instrument for that line and then withdraws the key from the mechanical or key lock of the switch, proceeds to the supplemen-

tary operative signal-lever with said key, and 60 lowers the outdoor signal controlling the section in advance the lever of which signal he is able to unlock with said key. On the signalman at B desiring to switch in on commencing duty he takes no action until a train arriving from the rear is passing his signal-box, when he draws out the small contact-switch 70 203 and holds it out until the train passes the signal controlling the entrance to the section in advance. The supplementary signal-lever 75 on the platform is then placed to "danger" and locked and the key taken to the signal-box, and by means of this key the signalman will then be able to switch in on that line. 80

It will be seen that the outdoor-signal battery and local-alarm circuit are utilized to release the cut-out lock when the signal-box is cut out. When the signal-box at B is cut in, the local-alarm circuit is as follows: from 85 battery 50 through wire 51, terminals 7, and from thence to terminal 8 of the cut-out switch 150, wire 90, from which the circuit divides into two branches, respectively including the bell 93 and the magnet 91, reuniting at 90 92, and from thence through contact 206, bridge 203, contact 205, wire 92' to alarm rail-contact 5, rail-contact 8 and thence back through the instrument to battery, as before.

Having now particularly described and ascertained the nature of my said invention and the manner in which it is to be performed, I declare that what I claim is—

1. In positive lock-and-block railway-control systems the prevention of the cutting out or exclusion of an intermediate cabin and its block-instrument and signal connections and the prevention of the cutting in or inclusion of the same until the rear block-section of said cabin is clear of vehicles and conflicting points and the like substantially as described. 100

2. In positive lock-and-block railway-control systems the operation of the electrically-controlled outdoor semaphore-signal 110 when electrically cut out by means of supplementary mechanical devices from any desired point as and for the purposes set forth substantially as described.

3. In positive lock-and-block railway-control systems the prevention of the concurrent working of the outdoor semaphore-signal by devices connected to the intermediate or excludable cabin and by supplementary mechanical devices at any desired point as 120 and for the purposes set forth substantially as described.

4. In positive lock-and-block railway-control systems the prevention of the manipulation of the cutting-out or switching-in devices of the block instrument in an intermediate or excludable cabin while in the block-sections of such cabin conflicting points are 125

6 set or outdoor signals indicate the line as foul as and for the purposes set forth substantially as described.

5. In positive lock-and-block railway-control systems the prevention of the transmission by the block instrument of a message "line clear" until all points and signals within the block-section are in normal safety position as and for the purposes set forth substantially as described.

6. In positive lock-and-block railway-control systems the prevention of the manipulation of the operative devices of points and outdoor signals of a block-section after 15 the transmission of "line clear" to the rear cabin until the train has arrived at a protecting-signal as and for the purposes set forth substantially as described.

7. In positive lock-and-block railway-control systems the combination with the block instrument of switching through-contacts having a key-lock and a check-bar operated (as also the said switching through-contacts) by the key of said lock and adapted to hold 20 and retain the slide-bar of said block instrument against manipulation while said block instrument is cut out of the system in the uniting of two block-sections into one continuous section as and for the purposes set forth substantially as herein described and explained.

8. In positive lock-and-block railway-control systems the combination with a block instrument having an electromechanical lock 35 and switching through-contacts of a check-bar adapted to engage the slide-bar of said instrument and operative only when said slide-bar is released by its electromechanical lock and when the train has passed out of the 40 section as and for the purposes set forth substantially as herein described and explained.

9. In positive lock-and-block railway-control systems the combination with a block instrument having an electromechanical lock 45 and switching through-contacts of a check-bar adapted to engage the slide-bar of said instrument and having an electromechanical lock thereon adapted to prevent its withdrawal from its retaining position on the 50 slide-bar of the block instrument until the closing of an electric circuit by a train on the permanent way and by a mechanically-operative switch in the cabin as and for the purposes set forth substantially as herein described and explained.

10. In positive lock-and-block railway-control systems the combination with the block instrument having an electromechanical lock 60 and switching through-contacts with a key-lock and a check-bar adapted to cross the slide-bar a rail-contact protecting points in the block-section a supplementary electro-mechanical lock on the slide-bar of the instrument (preferably bifurcated for the purpose) with the electromagnet of said supple-

70 mentary lock in a battery-circuit including said rail-contact (normally open) a check-bar or retaining-bolt under the armature-catch of said supplementary electromechanical lock, a locking-pin for the operative devices of said points and a handle or device for concurrently operating said last-mentioned check-bar of the supplementary electromechanical lock arresting said other check-bar of the key-lock and releasing said locking-pin as and for the purposes set forth substantially as herein described and explained.

75 11. In positive lock-and-block railway-control systems the combination with operating devices of a key-lock of a key non-withdrawable except when the block instrument is cut out or excluded from the system and adapted to operate the key-lock of manually-operative devices or an outdoor semaphore-signal and to be non-withdrawable from said latter 80 key-lock unless said devices are locked in normal danger position as and for the purposes set forth substantially as herein described and explained.

85 12. In positive lock-and-block railway systems the combination with the slide-bar of a block instrument and revolving switching through-contacts having a rack 103 and a pinion 104 of a check-bolt 101 adapted to take across a stop on said slide-bar and to be prevented from so taking across until an armature-catch on said slide-bar is lifted on the joining up of an electric circuit substantially as herein described and explained and as 90 illustrated in the drawings.

95 13. In positive lock-and-block railway systems the combination with the slide-bar of a block instrument and revolving switching through-contacts whose movement actuated a check-bolt 101 and said check-bolt of a stop 105 111 a permanent magnet 112 an electric magnet 113 and an armature-catch 114 substantially as herein described and explained and as 100 illustrated in the drawings.

110 14. In positive lock-and-block railway systems the combination and arrangement with the slide-bar of a block instrument and revolving switching through-contacts actuating a check-bar 101 of a supplemental or divisional slide-bar 121 an electromagnet 120 a 115 stop 123 and an armature-catch 124 substantially as herein described and explained and as 110 illustrated in the drawings.

120 15. In positive lock-and-block railway systems the combination and arrangement of a block instrument one limb having check-bars 101 of additional or supplemental check-bolts 125 and 126 a locking-pin 127 and draw-bars and operating-levers and mechanism of points substantially as herein described and explained and as 125 illustrated in the drawings.

125 16. In positive lock-and-block railway systems the combination with the slide-bar of the block instrument and rail-contacts as set forth of an outdoor signal-semaphore having 130

levers 142, 143 and 144 a flange or lip on one of them 145 a connecting-rod 140 having an elongated eye 141 and hauling-cords, re-
verser-magnet and arm substantially as
herein described and explained and as illus-
trated in the drawings.

5 In testimony whereof I have signed my

name to this specification in the presence of
two subscribing witnesses.

WILLIAM ROWE.

Witnesses:

FRED WALSH,
PERCY ATWELL.
